Primary Examiner—Brian N. Vinson*Attorney, Agent, or Firm*—Michael McGreal**[57]****CLAIM**

The ornamental design for a dispenser, as shown and described.

DESCRIPTION

FIG. 1 is a top, front, and left side perspective view of a dispenser showing our new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom view thereof;
 FIG. 8 is a top, front, and left side perspective view thereof, shown in a retracted position; and,
 FIG. 9 is a fragmentary front elevational view thereof, showing the closure element rotated to a vertical position.
